CONTAINER CLOSING APPARATUS

Stanley W. Dennis and Edgar Henschen, Baltimore, Md., assignors to Crown Cork & Seal Company, Inc., Baltimore, Md., a corporation of New York

Application January 24, 1947, Serial No. 723,987

12 Claims. (Cl. 226—88.1)

1

This invention relates to container closing apparatus of the type comprising a head by means of which closures are applied to containers as the result of the intermittent relative approach of the head and successive containers, and including means by which closures are transferred from a magazine to position for application between each closing action. One object of the invention is to provide, in such apparatus, improved transfer means in the form of a slide arranged to transport a closure, detached from a stack in the magazine, to applying position and support it in this position for application. Another object is to provide improved drive means for the slide. Another object is to provide means whereby apparatus primarily designed for the handling of closures of a certain diameter may be readily converted to handle closures of a smaller diameter. These and other objects are attained in the illustrative apparatus shown in the accompanying drawings in which

Figure 1 is a front elevation of a capping head in accordance with the invention,

Figure 2 is a side elevation of the head of Figure 1 broken away in part,

Figure 3 is a section on line 3—3 of Figure 1, Figure 4 is a section on line 4—4 of Figure 3,

Figure 5 is a plan view, enlarged, of a stack feed finger of which three appear in Figure 4,

Figure 6 is an end elevation of the finger of Figure 5,

Figure 7 is a section substantially on line 7—7 of Figure 3,

Figure 8 is a section on line 8—8 of Figure 7 with parts removed,

Figure 9 is a partial view like that of Figure 3 with parts in different relation,

Figures 10 and 11 are sections on lines 10—10 and 11—11, respectively, of Figure 7,

Figure 12 is a plan view of an adapter fitting,

Figure 13 is an elevation of the fitting of Figure 12 as seen from the right of the latter figure,

Figure 14 is a section on line 14—14 of Figure 12,

Figure 15 is a section on line 15—15 of Figure 12,

Figure 16 is a section on line 16—16 of Figure 15,

Figure 17 is a partial elevation, somewhat enlarged, of the head as seen from the right of Figure 2 with parts broken away, and

Figure 18 shows in elevation a stack of closures, somewhat enlarged, such as the particular apparatus illustrated is designed to apply.

Basically, the illustrated head is like that shown in Figure 11 of the patent to Huntley et al.

1,956,218 of April 24, 1934. In the said Figure 11, the closures are shown as being relatively flat although somewhat circumferentially shouldered. The caps shown in Figure 18 of the present drawings are of the type disclosed in the co-pending application of Stanley W. Dennis, Serial No. 723,630, filed January 22, 1947, now Patent No. 2,497,870 of February 21, 1950. The cap generally designated at 20 has a circular top wall 21, a depending skirt 22, and an out-turned radially corrugated peripheral flange 23. The skirt is slightly shouldered peripherally at 24 whereby to prevent undue nesting of the caps when stacked and to maintain the flanges a substantial distance apart. For a given size of bottle, the original blanks both for the closure shown in Figure 11 of the patent and Figure 18 of the present drawings have the same diameter. However, due to the substantial depth of the skirt in the case of the cap 20, this cap is of substantially smaller overall diameter than the cap of the patent. While the invention is by no means limited to conversion features, one of its objects, as previously stated, is to provide means whereby apparatus like that of the patent can readily be converted for the handling of the smaller diameter caps.

Referring particularly to Figures 1, 2 and 3, the capping head comprises a bracket 25 in the form of a cylinder, and in the present instance the bracket is provided with top and bottom sets of ears 26, 27 and 28, 29, rendering it mountable on a rotary turret in the manner disclosed in the patent to Stewart and Franz, No. 2,311,786 of February 23, 1943, this patent being referred to as providing a system in which the new head is well adapted for use though by no means limited thereto. Splined in the bracket for vertical reciprocation is the cylindrical stem portion 30 of a throat carrier 31, the top of the stem carrying a roller 3 for the purpose disclosed in the said Stewart and Franz patent. The carrier includes a base block 32 which provides a circular throat chamber 33 coaxial with the stem, an expandable throat 34 being disposed in the chamber in surrounding relation to a presser foot 35. The spring 36 which urges the throat and a foot abutment 37 upwardly seats at its lower end on a plate 38 supported through a tongue and groove at one end and at its other end by a pin 39 which extends between vertical flanges 40 and 41, Figure 17, at the rear end of block 32, plate 38 having an opening in which the throat is freely received. This structure is all like that of the Huntley and Rau patent.

At its outer end, block 32 is provided with a vertical cylindrical aperture 42 whose otherwise flat top margin is provided with equi-distantly spaced radially extending recesses 43, 44 and 45, these recesses having flat bottoms in the same horizontal plane. The opening 42 in the present instance is of a diameter to pass with slight clearance the relatively flat caps of the Huntley and Rau patent. According to the present invention, an adapter fitting in the form of a sleeve 46, see also Figures 12 to 16, has a lower portion 47 snugly inserted in opening 42 and an upper annular shoulder 48 seating on the margin of opening 42 and secured thereon by means of taper headed screws threaded into block 32 through openings 49 in the shoulder. The shoulder is flattened at 50 to fit against the flat outer face 51, Figures 3 and 4, of the base block. The shoulder is circumferentially undercut or rabbeted at 52 to provide a groove 53 in conjunction with the underlying margin of aperture 42. Internally the sleeve surface has an upper portion 54 which tapers downwardly to a cylindrical portion 55 whose diameter is slightly greater than that of the caps 20, and as here shown, there is a somewhat enlarged cylindrical surface portion 56 below portion 55. The inner lower margin of the sleeve is cut away at 57, leaving a full depth portion 58 which has a horizontal lower edge. Formed in the sleeve are three horizontally elongated slots 59, 60 and 61 which are respectively opposite the recesses 43, 44 and 45, the slots lying between horizontal planes of which the lower one, as here shown, intersects the cylindrical surface 55 while the top one intersects the lower part of the tapered surface 54.

Mounted in recesses 43, 44 and 45 are fingers 62, 63 and 64 pivoted on vertical pins 65, 66 and 67 which are received in aligned openings in the base block and sleeve shoulders. These fingers project into the sleeve interior through the openings 59, 60, and 61, and are all identical and are of a form most clearly shown in Figures 5 and 6.

Referring to the latter figures, the finger 62, 63, or 64 will be seen to have the form of a fish tail comprising vertically spaced upper and lower portions 68 and 69. The bottom surface of portion 68 is horizontal as is also the top surface of portion 69 and their spacing is somewhat greater than the thickness of the cap flange 23. Portion 68 has a surface 70 upwardly inclined from an edge 71 to provide a wedge formation whose thickness is greater than the spaces between the flanges 23 of the stacked caps. Behind portions 68 and 69, the finger has a bore 72 which receives the pivot pin and beyond the bore is an open ended radial slot 73.

Reference numeral 74 designates a ring segment slidably and rotatably received in groove 53 and carrying pins 75, 76 and 77 which are received in the slots as at 73 of the several fingers, and projecting radially outwardly of the ring is a finger 78.

Mounted on top of fitting 46, Figures 1, 2 and 3, and secured thereto by means of screws threaded into openings 79, Figure 12, is a vertical magazine cylinder 80 which has a vertical access slot 81 in its outer wall. The inner surface of the magazine cylinder includes upper and lower cylindrical portions 82 and 83 separated by a shoulder 84. The diameter of portion 82 is such as to enable it to receive a tubular package of caps of the type shown in the Huntley and Rau patent with the tube supported on the shoulder 84 as indicated in Figure 11 of the said patent. The

diameter of portion 83 is, as here shown, the same as that of the base block aperture 42 and is of a size to receive the package tube for the caps 20 shown in Figure 18, a marginal portion 85 of sleeve 46 projecting inwardly of portion 83 to provide a shoulder for the support of the package tube.

A transverse pin 86 is supported by the front part of bracket 25 and has pivotally mounted on its ends a pair of parallel bell crank levers 87 and 88 having downwardly projecting arms 89 and 90. The bell crank levers include forwardly projecting arms 91 and 92 to the ends of which are pivoted, on coaxial pins, rectangular blocks 93 and 94 slidable in horizontal grooves defined between lateral ribs 95, 96 and 97, 98 on the sides of the magazine cylinder 80, the rectangular blocks having been found to serve much more effectively than the rollers shown in the Huntley and Rau patent.

Reference numeral 99 designates a platform having upstanding ears 100 and 101 coaxially bored for the pivotal reception of a pin 102 supported in a transverse bore in the outer extremity of the base block 32. At its inner end, the platform has extensions 103 and 104, Figures 7 and 17, constituting keepers of the slightly hooked form shown in Figure 3. Extensions 43 and 44 support a transverse pivot pin 105 for a latch yoke 106 whose arms are spaced apart so as to be able to straddle the keepers 103 and 104. A pin 107 is rotatably mounted in the outer portions of the yoke arms and is retained against axial displacement by means of a peripheral groove 108 and a pin 109, pin 107 having at one end a head 110. Longitudinally slidable in a groove in the outer face of the opposite yoke arm is a plunger 111 which is retained by a plate 112 and is pressed by a spring 113 toward the adjacent flat beveled end of pin 107, the plunger being retractile by means of a finger 114 which projects through a slot in plate 112. Pin 107 has a flat 115 and, when plunger 111 is retracted, head 110 can be turned to bring the flat on top so that pin 107 can be swung under the keepers 103 and 104. When under the keepers and turned as in Figure 3, the platform 99 is locked in operative position and accidental release is prevented by the plunger 111.

The platform 99 has side walls 116 and 117 which are flat on top except for the ears 100 and 101, these walls being bounded inwardly by parallel grooves 118 and 119 which intersect the opposite sides of an opening 120 at the thickened inner end of the block 33 and coaxial with the throat chamber, the grooves terminating in recesses 121 and 122. Aperture 120 has a cylindrical surface 123 surmounting a downwardly flared surface 124 which serves as a guide for the bottle top. The platform 99 has a top central groove 125 which intersects the opening 120, parallel ribs 126 and 127 being provided between the inner and outer grooves and being substantially lower than the side walls. The platform has a central slot 128.

The slide 129 is in the form of a plate provided with parallel bottom grooves 130 and 131, Figure 11, which receive the rails 126 and 127 with the top of the slide no higher than the side walls 116 and 117. The front portion of the slide has a substantially continuous top surface 132 and has rearward extensions 133, 134 including depressed horizontal ledges 135 and 136 with bounding lateral walls 137 and 138 which are spaced apart a distance slightly greater than the diameter of

the cap to be applied, the tops of the walls being beveled as shown in Figures 7 and 10. The space between the extensions is bounded forwardly by a cross wall 139 from the lower portion of which projects a ledge 140 whose top is coplanar with ledges 135 and 136 and the latter are provided at their rear ends with stops 141 and 142 which, together with wall 139, provide three points centering means for a cap supported on the ledges, the height of the stops being only that necessary for effective action.

Projecting downwardly from the forward portion of the slide midway between its lateral edges and through slot 128 is a stud 143, here shown as tubular, provided with opposite lateral openings 144 and 145 which are elongated fore and aft. Surrounding the stud and guided thereby for rotary movement is a sleeve 146 having opposite circular openings which receive a pin 147 with only slight clearance, the pin passing also through slots 144 and 145. The ends of pin 147 are in connection with arms 89 and 90 by means of links 148 and 149. Stud 143 serves to support the pin with capability of swinging about the stud axis. Movement of the pin by the bell crank levers is transmitted to sleeve 146 and by the latter to the stud. This swivelling arrangement eliminates any tendency of the slide to bind by reason of skewing action of the pin.

In Figures 3 and 4, the apparatus is in normal or rest position. Portions 69 of the magazine fingers are in a position out from underneath the stack and the stack is supported on the finger portions 68 which, in swinging counterclockwise to the position shown in Figure 4, detached the lowermost cap with a positive wedging action so that the latter was deposited on the front or left end surface 132 of the slide 129. Assuming a cap to be supported on the ledges 135, 136 and 140 and centered relative to the capping throat by wall 139 and stops 141 and 142, its top surface is spaced below the presser foot 35 a distance slightly greater than the thickness of the stops. When a bottle is now lifted into the opening 120 and into engagement with the cap, the latter will, first of all, be lifted against the presser foot so that its flange will be above the stops. As the rise of the bottle continues, the throat carrier is lifted as a whole so that the bell crank levers 87 and 88 are swung clockwise to project the slide forwardly, toward the left and also, through a link 150 arranged between arm 90 and pin 78, to swing the ring segment 74 clockwise and, hence, the magazine fingers also clockwise. As finger portion 68 moves out from under the stack, portions 69 come beneath the stack and the latter drops thereon. As the slide is projected forwardly toward the left, the cap on the slide surface 132 is held against movement therewith by the extension 58 of a sleeve 46, the lower edge of the extension lying closely adjacent the top of the slide. Consequently, as the slide moves to its outer or forward limit, Figure 9, the detached cap falls onto the rear supporting ledges of the slide and is centered thereon by the centering means. As the upward movement of the throat carrier is arrested through abutment with the bracket 25, the throat 34 is projected somewhat downwardly against the action of spring 36 and thereafter, the presser foot spring yields and the cap is applied. The capping pressure is considerably less than that required in applying the cap of the Huntley and Rau patent since the cap 20 here being applied has a preformed skirt which makes unnecessary the rather severe iron-

ing pressure required in the application of the relatively flat cap. Due to this large reduction in the capping pressure, the compensating means for the cradle cam of the Stewart and Franz patent may be constituted by a simple spring of suitable strength.

When the cap has been applied and the bottle lowered, the throat carrier is permitted to lower so that the parts resume rest position, the cap 10 on the rear right-hand end ledges of the slide being brought beneath the throat, overthrow of the cap being prevented by the stops, and the magazine fingers swung counterclockwise to detach the lowermost cap from the stack and deposit it on the plane surface 132 of the slide. The return of the parts is limited by the engagement of sleeve 146 with portion 99 of the platform.

Considering the described apparatus in the aspect of conversion of the Huntley and Rau head, it will be seen that the latter remains basically the same. The throat carrier, which is the principal piece of mechanism, is changed merely by the insertion of the adapter fitting, the substitution of the described form of magazine fingers, and the substitution, desirably, of the slide blocks 93 and 94 for the rollers previously used. Platform 99 with its slide, is easily substitutable for the platform of the patent and the latch means shown in the patent may be retained or the preferred latch 20 means hereinbefore described substituted. It will be understood, however, that the described apparatus is not necessarily contemplated merely from the standpoint of conversion but also from the general standpoint of a new and efficient association of parts in a capping head, and, further, that variations in the described form and arrangement of parts are possible under the invention as defined in the following claims.

We claim:

1. In closure applying apparatus comprising a member providing a vertical opening of a size to pass closures of a certain diameter, and recesses in the top of said member around said opening for the reception of oscillatory closure feeding fingers, the combination of means for adapting said apparatus for the handling of closures of smaller diameter, said means comprising an adapter in the form of a sleeve inserted in said opening, the interior surface of said adapter sleeve including an upper portion tapering downwardly to a lower cylindrical portion said cylindrical portion having its upper end adjacent the top of said recesses and having a diameter slightly greater than that of said smaller closures, apertures in said sleeve opposite said recesses, and oscillatory closure feeding fingers pivoted in said recesses and projecting operatively through said apertures.
2. In closure applying apparatus comprising a member providing a vertical opening of a size to pass closures of a certain diameter, and recesses in the top of said member around said opening for the reception of oscillatory closure feeding fingers, the combination of means for adapting said apparatus for the handling of closures of smaller diameter, said means comprising an adapter in the form of a sleeve inserted in said opening, the interior surface of said adapter sleeve including an upper portion tapering downwardly to a lower cylindrical portion, said cylindrical portion having its upper end adjacent the top of said recesses and having a diameter slightly greater than that of said smaller closures, apertures in said sleeve opposite said recesses, and oscillatory closure feeding fingers

pivoted in said recesses and projecting operatively through said apertures, said sleeve having a peripheral shoulder secured against the upper margin of said opening, the lower part of said shoulder being provided with a rabbet to provide a groove in conjunction with said margins, and an operating ring for said fingers rotatable in said groove.

3. Closure applying apparatus comprising a head including a forwardly positioned, vertical magazine and a throat disposed on a vertical axis in horizontally and rearwardly spaced relation to the magazine, means for detaching closures from the bottom of a stack in said magazine, guide means extending between the lower ends of said magazine and throat, a slide reciprocable in said guide means between forwardly and rearwardly projected positions, said slide having a forward surface which in the rearwardly projected position is adapted to receive and support a detached closure and having horizontally spaced apart rear extensions presenting opposed ledges below the level of said surface adapted to support a closure, means restraining a closure on said forward surface from movement with the slide during forward movement of the slide so that said closure drops onto said ledges when the slide reaches the forwardly projected position, an abutment portion on the slide engaging the closure on said ledges so that said closure is carried beneath said throat when the slide is projected rearwardly, and means for reciprocating said slide and operating said detaching means in timed relation.

4. Closure applying apparatus comprising a head including a forwardly positioned, vertical magazine and a throat disposed on a vertical axis in horizontally and rearwardly spaced relation to the magazine, means for detaching closures from the bottom of a stack in said magazine, guide means extending between the lower ends of said magazine and throat, a slide reciprocable in said guide means between forwardly and rearwardly projected positions, said slide having a forward surface which in the rearwardly projected position is adapted to receive and support a detached closure and having horizontally spaced apart rear extensions presenting opposed ledges below the level of said surface adapted to support a closure, means restraining a closure on said forward surface from movement with the slide during forward movement of the slide so that said closure drops onto said ledges when the slide reaches the forwardly projected position, an abutment portion on the slide engaging the closure on said ledges so that it is carried beneath said throat when the slide projected rearwardly, stops on the outer ends of said ledges preventing overthrow of the advanced closure, and means for reciprocating said slide and operating said detaching means in timed relation.

5. Apparatus according to claim 3 including a

guide sleeve at the lower end of the magazine, the forward portion of said guide sleeve extending close to said slide surface and serving as the restraining means.

6. Apparatus according to claim 4 including a presser foot in said throat normally spring-urged downwardly and having a lower limit position wherein it is spaced above a closure beneath said throat a distance greater than the height of said stops.

7. For use in closure applying apparatus, a closure transfer slide intended for horizontal reciprocation and having at one end a closure supporting surface at one level and integral, rigid extensions at the other end including upwardly unobstructed closure supporting ledges at a lower level.

8. A slide according to claim 7 including an abutment at the inner ends of said ledges for a closure supported thereon.

9. A slide according to claim 7 including closure centering means comprising an abutment at the inner ends of said ledges and stops on the outer ends of said ledges.

10. In apparatus of the class described, a slide and guide means therefor, a stud projecting from one face of said slide substantially midway between the lateral edges thereof, a sleeve rotatable on said stud, a pin, said stud and sleeve being transversely apertured to receive said pin with capability of swinging relative to the stud but not to said sleeve, and operating arms engaging the ends of said pin.

11. Apparatus according to claim 10 including a stop on said guide means engageable by said sleeve to limit travel of the slide in one direction.

12. Apparatus of the class described comprising a bracket, a throat carrier supported from the bracket for vertical reciprocation, a vertical closure magazine supported by the carrier, a horizontal slide for transferring closures from the magazine to applying position, slide actuating means comprising a pair of parallel bell crank levers pivotally supported from the bracket on a horizontal axis and having downwardly projecting arms in operative connection with the slide and outwardly projecting arms straddling the magazine, horizontal grooves on the magazine, and rectangular blocks pivoted to the last-mentioned arms and slidable in said grooves.
